(57) **CLAIM**

The ornamental design for an upright deep cleaner, as shown and described.

DESCRIPTION

FIG. 1 is a front perspective view of an upright deep cleaner showing my new design;

FIG. 2 is a front view thereof;

FIG. 3 is a rear view thereof;

FIG. 4 is a right side view thereof;

FIG. 5 is a left side view thereof;

FIG. 6 is an enlarged top view of the upright deep cleaner of FIG. 1; and,

FIG. 7 is an enlarged bottom view of the upright deep cleaner of FIG. 1.

The details of the upright deep cleaner shown in broken lines form no part of the claimed design.

1 Claim, 7 Drawing Sheets
